SINGING BIRD CLOCK

Pearl D. Davis and Edward Pratt Porter, Jr.,
Bellefontaine, Ohio

Application August 13, 1947, Serial No. 768,450

1 Claim. (Cl. 58—12)

1

The present invention relates to clocks, and more specifically to clocks of the type embodying novel and ornamental sound-producing mechanisms accompanied by a bird-simulating figure.

The primary object of this invention is to provide in conjunction with a clock, a bird-simulating figure capable of novel movement, and a mechanical sound-producing mechanism for simulating the song of a bird at time intervals of the operation of the clock.

It is another object of the present invention to provide mechanism of the character described, which is mechanically efficient, yet structurally simple, and which utilizes, and may be adapted for use with, the usual clock mechanisms without extensive modification thereto.

These and various additional objects and advantages will be made more readily apparent with a further and more detailed understanding of the present invention, which may be had by reference to the following description and the accompanying drawings wherein:

Fig. 1 is a front elevational view of a novelty clock formed in accordance with the present invention;

Fig. 2 is a top plan view of the clock mechanism with the clock casing shown in horizontal section;

Fig. 3 is a vertical sectional view taken along a plane indicated by the line 3—3 of Fig. 2;

Fig. 4 is a similar view taken along the line 4—4 of Fig. 2.

Fig. 5 is a longitudinal vertical sectional view taken through the bird-simulating figure mounted upon the clock casing;

Fig. 6 is a top plan view, partially in horizontal section, of the bird-simulating figure.

Fig. 7 is a detailed vertical sectional view taken along the line 7—7 of Fig. 6;

Fig. 8 is a detailed vertical sectional view taken along the line 8—8 of Fig. 5;

Fig. 9 is a vertical sectional view taken along the line 9—9 of Fig. 4, and disclosing in detail the whistle device associated with the present invention.

Referring now to the drawings, the numeral 10 designates a flat base upon which is mounted a substantially rectangular cabinet or casing 11 which serves as a housing for a clock movement 12 driven by a suitable electric synchronous motor 13. The clock movement 12, in the usual manner, is provided with a plurality of co-axial shafts 14 which carry exteriorly disposed hour, minute, and second hands positioned in regis-

tration with the usual clock dial 15. The minute hand shaft of the clock movement 12 is provided with a shaft extension 16 which extends rearwardly from the clock movement housing, 5 and carries at its outer end a star-shaped cam or spur gear 17. This latter spur gear 17 is in turn provided with four equally spaced node portions, each of which is provided with a rearwardly extending stud 18. Mounted adjacent the spur gear 17, in vertical alignment with the outer end thereof, is a swinging armature or circuit breaker 19 which, as shown in Fig. 3, is hingedly mounted and engageable with the rearwardly projecting studs 18 of the gear as the same approach a substantially horizontal plane. The gear, upon rotation of the minute hand shaft, serves to impart a limited swinging movement to the circuit breaker 19 in a clockwise direction. Disposed adjacent the lower end of the 10 circuit breaker are a pair of electrical circuit terminals 20, which serve in conjunction with the swinging circuit breaker 19 to provide a switch for a second and relatively small electric motor 21. It will be seen, that as the spur gear 17 undergoes rotation at time intervals with respect to the minute hand, and due to the ninety degree location of the node portions, the circuit breaker 19 will be brought into engagement with the open contacts 20 of the switch at 15 minute 15 intervals of the clock operation. A manually operable shaft 22, which extends rearwardly of the casing 11, carries a cam stud 23 at its inner end which is engageable with the swinging circuit breaker 19, whereby the switch may be closed 20 independently of the clock operation.

As shown particularly in Fig. 3 of the drawings, the two electric motors 13 and 21 utilize a common electrical outlet conduit 24, with the smaller electric motor 21 being connected in series with the synchronous motor 13. The smaller electric motor 21, disposed adjacent the clock movement, is provided with an armature shaft 25 which carries at its outer end a wheel 26 having a single throw crank arm 27. Pivotally linked 25 with the crank arm 27 is the upper end of a connecting rod 28 which is pivotally attached, as at 29, to the lower movable portion of a stationary bellows 30. The bellows 30 is provided with a forced air outlet 31 around which is mounted the intake opening of a whistle 32. The latter whistle comprises a generally cylindrical and tubular body, provided with a moon-shaped opening 33 through which forced air, introduced by way of the opening 31, is discharged from the whistle to produce a sound of given pitch. The

whistle 32 is further provided with a slidable piston or trombone valve 34 which serves to vary the tone or pitch of the whistle. The piston 34 is carried upon a relatively elongated shaft 35 which is pivotally linked to the outer end of a spring-pressed cam follower arm 36. The up and down movement of the piston 34 within the whistle 32 is controlled by means of a cam gear 37 which is driven by the small electric motor 21 by way of a reduction gear system 38 disposed between the armature shaft 25 of the motor and the axially disposed shaft of the cam gear 37. The cam follower arm 36 is provided with a downwardly extending wedge-shaped pintle 39 which is maintained in meshing engagement with the peripheral surface of the cam gear, and is subject to vertical displacement in accordance with the nodes and dwells of the gear.

It will be seen, that upon operation of the electric motor 21, the bellows 30 will be driven by the reciprocating movement of the connecting rod 28 to furnish forced air for the whistle 32, at the same time the cam gear 37 will be driven at a relatively slower rate of speed, whereby the piston 34 carried within the whistle will be caused to move in an up and down motion, in accordance with the nodes and dwells of the cam gear, to vary the pitch and tone of the whistle 32. By predetermined measurement, the depth and height of the nodes and dwells of the cam gear 37 may be controlled to simulate or produce a certain bird song within the associated whistle 32, whereby a bird song is simulated in a realistic and pleasing manner.

Mounted upon a hollow perch 40, carried upon the upper surface of the casing 11, is a hollow bird figure 41 which, for purposes of ornamentation, is confined within a bird cage 42. The bird figure 41 may advantageously be provided with an outer coating of feathers to simulate a realistic appearance, and is constructed so as to have a movable beak 42', a head 43 arranged for limited rotational movement, and a tail 44 which is pivotally attached to the body portion of the figure, as at 45, for a fluttering movement. The movement of the various portions of the bird figure 41 is accomplished by means of a linkage disposed within the body of the figure, and responsive to the movement of the cam gear 37, so that movement within the bird figure is synchronized with the bird song produced by the whistle 32. The tail and beak movement of the bird is accomplished by means of a pivotally mounted lever 46 which is connected at one end with the cam follower arm 36, as at 46a, and carries at its opposite end a vertically arising shaft 47. This shaft, in turn, is linked through the body of the bird figure with one arm of a T-shaped and pivotally mounted lever 48. The opposite arms of the lever 48 are pivotally linked respectively to the inner end of a tail extension shaft 49, which is rigidly attached to the pivotally mounted tail 44, and to one end of a connecting rod 50 which is attached at its opposite end to a pivotally mounted bell crank lever 51 pivotally attached, as at 51a, to the movable beak 42' of the bird.

In view of the above described relationship between the tail and beak portions of the bird figure and the cam gear 37, it will be seen that upon rotation of the cam gear the beak and tail portions of the figure will be moved at relatively high speeds in accordance with the formation of the peripheral edge of the gear, whereby the movement of the beak and tail of the figure is more or less synchronized with the changes of

tone of the whistle 32, thus affording a degree of realism to the movements of the bird figure.

As before stated, the bird figure 41 is provided with a head portion 43 which is mounted upon the body of the bird for limited rotational movement to simulate the turning of the head of the bird. This latter movement, is accomplished by means of a second pivotally mounted lever arm 52 disposed adjacent the arm 46, and fulcrumed by a common pin 53. Rocking movement is imparted to the lever arm 52 by means of a downwardly projecting arm 52a disposed at one end of the lever and engageable with a plurality of studs 37a which project outwardly from the face of the cam gear 37. These studs are radially disposed, and serve upon rotation of the gear to engage the arm extension and force the same upwardly at desired intervals. The outer end of the lever arm 52 pivotally carries the lower end of a vertically arising shaft 54 which extends through the hollow perch 40 and upwardly into the interior of the bird figure 41, in the same manner as the shaft 47. The upper end of this shaft is pivotally attached as at 54a, to one arm of a centrally fulcrumed bell crank lever 55 disposed adjacent the T-shaped lever 48. The opposite end of the bell crank lever 55 carries a connecting rod 56 which is linked at its opposite end, as at 56a, to the outer end of a crank arm 57 rigidly carried at the lower end of a shaft 58. This shaft 58 is rigidly connected with the head portion 43 of the figure, and upon oscillatory movement, serves to impart a limited rotation to the head to simulate the turning movement thereto. The shaft 58 is rotatably supported within a bearing collar 59 which, in turn, is attached to the fulcrum point of the bell crank lever 51. It will be seen, that due to the relative spacing between the studs 37a, disposed upon the outer face of the cam gear 37, the turning movement of the head of the bird will be relatively slower in cycle than the movement of the tail and beak of the figure. Also, due to the associated disposition of the leverage associated with the beak and head of the bird, the beak 42 will remain movable during the limited rotation of the head of the bird, further increasing the realistic qualities of the figure in accordance with the bird song produced by the whistle 32.

In view of the foregoing, it will be seen that the present invention provides an attractive and ornamental novel clock including a singing and movable bird figure operated independently of the clock mechanism by means of a relatively small and inexpensive electric motor whose actuation is controlled at time intervals of operation of the associated clock movement.

While a preferred form of the present invention has been disclosed in detail, it will be manifest that various modifications as to details of construction may be accomplished without departing from the spirit of the invention or the scope of the following claim:

We claim:

In a novelty clock, a casing, a clock movement including a minute hand shaft, an electric synchronous motor for said clock movement, a cam carried by the minute hand shaft of said clock movement, a switch having a movable circuit-breaker arm engageable with said cam for opening and closing said switch at time intervals of operation of said clock movement, a second electric motor having an operating circuit controlled

by said switch, a whistle, a piston slidably mounted within said whistle for varying the pitch thereof, a bellows operated by said second motor for supplying forced air to said whistle, a cam wheel driven by said second motor, a cam follower engageable with said cam wheel and connected with said piston for moving the latter within said whistle, a movable bird-simulating figure carried exteriorly of said casing, and means responsive to the operation of said cam wheel for 10 effecting movement within said figure.
